(57) **CLAIM**

I claim the ornamental design for a collapsible accessory holder for a lighting device, as shown and described.

DESCRIPTION

FIG. 1 is a perspective view of the collapsible accessory holder for a lighting device showing the new design, with the collapsible accessory holder in its expanded form;

FIG. 2 is a front elevational view of the collapsible accessory holder depicted in FIG. 1;

FIG. 3 is a rear elevational view of the collapsible accessory holder depicted in FIG. 1;

FIG. 4 is a left side elevational view thereof of the collapsible accessory holder depicted in FIG. 1;

FIG. 5 is a right side elevational view thereof of the collapsible accessory holder depicted in FIG. 1;

FIG. 6 is a top plan view thereof of the collapsible accessory holder depicted in FIG. 1; and

FIG. 7 is a bottom plan view thereof of the collapsible accessory holder depicted in FIG. 1.

FIG. 8 is a perspective view of the collapsible accessory holder showing the new design, with the collapsible accessory holder for a lighting device in its collapsed form;

FIG. 9 is a front elevational view of the collapsible accessory holder depicted in FIG. 8;

FIG. 10 is a rear elevational view thereof of the collapsible accessory holder depicted in FIG. 8;

FIG. 11 is a left side elevational view thereof of the collapsible accessory holder depicted in FIG. 8;

FIG. 12 is a right side elevational view thereof of the collapsible accessory holder depicted in FIG. 8;

FIG. 13 is a top plan view thereof of the collapsible accessory holder depicted in FIG. 8; and,

FIG. 14 is a bottom plan view thereof of the collapsible accessory holder depicted in FIG. 8.

The broken lines illustrating portions of the collapsible accessory holder for a lighting device form no part of the claimed design.

1 Claim, 7 Drawing Sheets
